INVENTOR.

BY Morris Litman.
Walter C. Ross, Attorney.

UNITED STATES PATENT OFFICE

2,313,882

RECEPTACLE

Morris Litman, Springfield, Mass.

Application June 15, 1942, Serial No. 447,081

2 Claims. (Cl. 294—71)

This invention relates to improvements in receptacles and is directed more particularly to improvements in receptacles for retrieving objects.

The principal objects of the invention are directed to the provision of a receptacle having relatively swingable closure means all constructed and arranged whereby the device may be placed over an object and operated so as to pick up and retrieve the object.

The novel features of the invention are adapted for broad application but is particularly adapted for picking up or retrieving such as incendiary bombs and the like.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawing wherein:

Fig. 1 is an end elevational view of a receptacle apparatus embodying the novel features of the invention;

Fig. 2 is a small scale side elevational view of the apparatus shown in Fig. 1;

Fig. 3 is a small scale end elevational view of the apparatus shown in Figs. 1 and 2 showing the closure means in open position; and

Fig. 4 is a transverse sectional elevational view through the apparatus with the closure means in open position.

Referring now to the drawing more in detail, the invention will be fully described.

A receptacle 2 has top, end and side walls 4, 6 and 8 and is open on its lower side. The receptacle may be made from various materials but will preferably be made from metal. A handle or bale 10 is provided which is secured to the upper wall 4.

Closure means consists of members 12, has side walls 14 hinged at 16 to the walls 8, and bottom and end walls 18 and 20 secured to said walls 14. The closure members 12 are preferably made in the form of scoops adapted to pick up objects as well as to close the open lower side of the receptacle.

A handle 22 has end parts 24 slidably in guides 26 secured to the end walls 6. Braces 30 arranged in pairs at opposite ends of the receptacle are pivoted at 32 to the end walls of the closure members and are pivoted intermediate their

ends to the ends of the handle parts 24 as at 34. Tension springs 36 have their opposite ends connected to the upper ends of the braces at 38. The springs yieldingly resist movement of the braces from the closed position of the closure members shown in Fig. 1 to the open position thereof shown in Figs. 3 and 4 and urge the closure members to their closed position. As previously stated, the closure members are arranged to efficiently close the open end of the receptacle and to function as scoops when moving from open to their closed position.

The braces may be employed for supporting the structure with the closure means in the closed position of Fig. 1 as well as to actuate the closure members in their swinging movements.

In operation the device may be located over an object to be retrieved and with the hand grasping the members 10 and 22 the latter may be depressed to act on the braces and open the closure means. When the member 22 is released the springs 36 operate to move the braces which swing the closure members to their closed position so that they scoop up the object and close the receptacle. If the object is resting on the floor the braces may support the device so that by pressing on the member 22 the closure members are opened by the swinging of the braces.

The device is adapted for broad use but is particularly adapted for picking up and containing incendiary bombs and the like. To that end the closure members and the receptacle, if desired, may be lined with some non-inflammable material indicated by 40, such as asbestos or the like. There may be supporting means in the form of a transverse or longitudinal member or members such as 42 in the receptacle for supporting fire extinguishing material for release by the heat of the object. As an example, there may be a sack on the supporting means that contains sand or some other material adapted to extinguish and smother the fire of the bomb or other object. The sack will be ruptured by the fire or heat of the bomb so as to release the extinguishing material onto the bomb supported by the closed closure members.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning

and purview and range of equivalency of the appended claims are therefore intended to be embraced therein.

What it is desired to claim and secure by Letters Patent of the United States is:

1. A device of the class described comprising in combination, a receptacle having top, side and end walls and an open lower side, closure members having side walls hinged at upper longitudinal edges to lower longitudinal edges of the side walls of the receptacle and provided with relatively inclined lower walls and end walls, said closure members arranged so that when in closed position their side and end walls are disposed as continuations of the end and side walls of the end and side walls of the receptacle with the lower walls and end walls in abutting relation, operating means slidable up and down on the end walls of the receptacle, a pair of actuating members at each end of the receptacle, the members of each pair arranged relatively diagonally and pivoted intermediate their ends to the operating means for relative swinging movements, pivotal connections between each actuating member and an adjacent end wall of a closure member and disposed below said first named pivotal connections, and tension spring means connecting the upper ends of each pair of actuating members.

2. A device of the class described comprising in combination, a receptacle having top, side and end walls and an open lower side, closure members having side walls hinged at upper longitudinal edges to lower longitudinal edges of the side walls of the receptacle and provided with relatively inclined lower walls and end walls, said closure members arranged so that when in closed position their side and end walls are disposed as continuations of the end and side walls of the end and side walls of the receptacle with the lower walls and end walls in abutting relation, operating means slidable up and down on the end walls of the receptacle, a pair of actuating members at each end of the receptacle, the members of each pair arranged relatively diagonally and pivoted intermediate their ends to the operating means for relative swinging movements, pivotal connections between each actuating member and an adjacent end wall of a closure member and disposed below said first named pivotal connections, tension spring means connecting the upper ends of each pair of actuating members, and the lower ends of the actuating members extending beyond the pivotal connections of the said members and closure end walls adapted to serve as supports for the device when the closure members are in closed position.

MORRIS LITMAN.
